[57] CLAIM

The ornamental design for a shoe upper, as shown and described.

DESCRIPTION

FIG. 1 is a right side elevational view of a shoe upper showing my new design;
FIG. 2 is a top plan view thereof;
FIG. 3 is a bottom plan view thereof;
FIG. 4 is a left side elevational view thereof;
FIG. 5 is a front elevational view thereof;
FIG. 6 is a rear elevational view thereof;
FIG. 7 is a right side elevational view of a shoe upper showing an alternate embodiment of my new design;
FIG. 8 is a top plan view thereof;
FIG. 9 is a bottom plan view thereof;
FIG. 10 is a left side elevational view thereof;
FIG. 11 is a front elevational view thereof; and
FIG. 12 is a rear elevational view thereof.
The broken line showing of a shoe sole in FIGS. 1 and 7 is for illustrative purposes only and forms no part of the claimed design.

*Fig. 1.**Fig. 2.**Fig. 3.*

*Fig. 4.**Fig. 5.**Fig. 6.*

*Fig. 7.**Fig. 8.**Fig. 9.*

*Fig. 10.**Fig. 11.**Fig. 12.*
